UNITED STATES PATENT OFFICE

161,478

DENTAL MIRROR

Stanley F. Lundgren, Minneapolis, Minn.

Application December 1, 1949, Serial No. 6,357

Term of patent 14 years

(Cl. D24—5)

To all whom it may concern:

Be it known that I, Stanley F. Lundgren, a citizen of the United States, residing at 4036 13th Avenue South, Minneapolis, Minnesota, have invented a new, original, and ornamental Design for a Dental Mirror, of which the following is a description, reference being had to the accompanying drawings, forming a part hereof.

Fig. 1 is a perspective view of a dental mirror, showing my new design;

Fig. 2 is a side elevational view thereof;

Fig. 3 is another perspective view thereof viewing the reflecting mirror at right angles thereto; and

Fig. 4 is a perspective view thereof;

I claim:

The ornamental design for a dental mirror, substantially as shown.

STANLEY F. LUNDGREN.
